WILLIAM H. MINER, OF CHICAGO, ILLINOIS.

DRAFT-RIGGING FOR RAILWAY-CARS.

1,203,231.

Specification of Letters Patent. Patented Oct. 31, 1916.

Application filed December 1, 1913. Serial No. 803,904.

To all whom it may concern:

Be it known that I, WILLIAM H. MINER, a citizen of the United States, residing at Chicago, in the county of Cook and State 5 of Illinois, have invented a certain new and useful Improvement in Draft-Rigging for Railway-Cars, of which the following is a full, clear, concise, and exact description, reference being had to the accompanying 10 drawings, forming a part of this specification.

My invention relates to improvements in draft rigging for railway cars.

The object of my invention is to provide 15 a draft rigging having a comparatively easy initial action on forward movement of the draw bar.

In the drawings forming a part of this specification—Figure 1 is a plan view partly 20 in horizontal section, one of the front stop members being shown in horizontal section on line 1—1 of Fig. 2, of a draft rigging embodying my invention; Fig. 2 is a side elevation of the front follower and a vertical longitudinal section taken through one 25 of the front stop members on line 2—2 of Fig. 1; Fig. 3 is a side elevation of the front follower and one of the front stop members; Fig. 4 is a cross section taken on line 30 4—4 of Fig. 2.

Referring to the drawings the numerals 5, 5 represent draft sills or parts of the car frame to which the draft rigging is applied; 6 a draw bar having a draft yoke 7 suitably 35 secured thereto; a draft gear 8 mounted within the yoke, the said draft gear illustrated in the drawings comprising a shell 9 and compression resisting parts 10 within the shell.

40 The numeral 11 represents a front follower; 12, 12 rear stop members suitably secured to the draft members, preferably by the rivets 13, 13, and 14, 14 the front stop members. The front stop members are 45 mounted between the draft sills, one on either sill, and are counterparts of each other. I therefore describe one of said stop members 14. It consists of a shell 15, preferably with two hollow spring chambers 50 30, 30 arranged one above the other, as illustrated in Fig. 2 of the drawings, each of said spring chambers being open at its rear end 16 and closed at its front end by the preferably integral plate 17, the forward end of 55 the shell being provided with a flange 18, which is preferably integral with and for-

wardly extended from the inner wall 19 of the shell 15, the flange 18 and the shell 15 being provided with suitable means, preferably the rivets 20, to rigidly secure the 60 same to the adjacent draft member 5. In preferable construction the shell 15 is provided with the openings 21 along its inner face to permit the easy riveting of the same to the draft sill 5. A hollow casing 22, open 65 at its forward end 23 and closed at its rear end by the preferably integral plate 24, is provided for each spring chamber. In each spring chamber a preferably helical spring 25 is mounted at the forward end against 70 the wall 17 of the shell 15, and at its rear end against the wall 24 of the casing 22. The wall 24 of the casing 22 is preferably 75 provided with a shoulder 26 adapted to engage against the rear end of the shell 15, and limit the inward movement of the casing. The said casings of the front stop members are seated at their rear ends against the forward face 27 of the front follower 11.

In normal position of the parts of the 80 draft rigging, as illustrated in Fig. 1 of the drawings, the hollow casings 22, 22 are rearwardly extended from the shell 15, and on forward movement of the draw bar the front follower moves the said casings forwardly, 85 the forward movement thereof being resisted by the springs within the casings until the shoulders 26 engage the shells 15, whereupon the forward movement of the front follower determines, and the parts of the 90 draft gear are brought into compression resisting action therewith. On rearward movement of the draw bar the springs in the front stop members do not serve to resist the draw bar's movement. 95

In preferable construction the plates 24 of the casings 22 on either stop member are joined by the connecting plate 31, there being a chamber 32 provided between the spring chambers in each stop member for 100 the passage of a bolt 33 passing at its forward end through a flange 35 in the stop member, and provided with a nut 36 seated against said flange, the said bolt at its rear end being provided with a head 37 countersunk in the connecting plate 31, the bolt serving to limit the rearward movement of the casings 22, and to retain the said casings in their assembled relation with the shell 15. 105

I claim:—

1. In a draft rigging for railway cars, oppositely arranged stop members, each com-

prising a shell having a plurality of spring chambers arranged one above the other, and springs in each of said chambers.

2. In a draft rigging for railway cars, in combination, draft members, a pair of oppositely arranged stop members secured thereto, a spring chamber in each stop member, a spring for each chamber, a follower, a draw bar and a draft gear connected to the draw bar, the springs being adapted to yield to the pressure of the follower on forward movement of the draw bar before the draft gear is brought into compression resisting action.
- 15 3. In a draft rigging for railway cars, in combination, draft members, a pair of oppositely arranged stop members secured thereto, a spring chamber in each stop member, a spring for each chamber, a follower, a draw 20 bar and a draft gear connected to the draw bar, the springs being adapted to yield to the pressure of the follower on forward movement of the draw bar, and until the follower abuts the stop members, before the draft 25 gear is brought into compression resisting action.

4. In a draft rigging for railway cars, stop members, each comprising a rigid mem-

ber, a movable spring seat, a spring seated between the movable spring seat and the rigid member, and a bolt between the rigid member and the movable spring seat to limit the expansion of the spring.

5. In a draft rigging for railway cars, stop members, each comprising a shell, a plurality of spring chambers in the shell, a spring in each of said chambers, a movable spring seat for the outer ends of the springs, and a bolt passing between the spring chambers connecting the movable spring seat to the shell to limit the expanding movement of the springs.

6. In a draft rigging for railway cars, the combination with draft members adapted to receive shock absorbing mechanism and followers therebetween, of front and rear sets of stop members secured to the draft members, the stops of one of said sets being each provided with a preliminary compression spring which is operated prior to the operation of the shock absorbing mechanism.

WILLIAM H. MINER.
